GRINDING MACHINE

Thor H. Ljunggren, Charlestown, N. H., assignor
to Bryant Chucking Grinder Company, Spring-
field, Vt., a corporation of Vermont

Application August 22, 1942, Serial No. 455,737

31 Claims. (Cl. 51—50)

1

This invention relates to metal working machines, and in its more specific aspects, to grinding machines.

One object of the invention is to provide improved controls for the cycle of operation.

A further object is to provide mechanism for moving the work and grinding wheel operated by fluid pressure, preferably hydraulic, together with electrical control of the fluid pressure mechanism.

Still another object is to provide for an automatic cycle of operations including rough and finish grinding with truing of the grinding wheel between the rough and finish grindings and with limit stops independently adjustable to determine the limits of wheel feed for both rough and finish grinding.

A further object is to provide for a feed and retractive motion of predetermined extent and superposed thereon an additional small feed increment to compensate for wheel wear and truing.

For a complete understanding of this invention, reference may be had to the accompanying drawings in which

Figures 1 and 2 are fragmentary front and top plan views of an internal grinding machine embodying the invention.

Figure 1a is a detail sectional view on line 1a—1a of Figure 1.

Figure 3 is a detail sectional view on line 3—3 of Figure 1.

Figures 4 and 5 are detail sectional views on lines 4—4 and 5—5, respectively, of Figure 3.

Figures 6 and 7 are detail sectional views on lines 6—6 and 7—7, respectively, of Figure 5.

Figure 8 is a fragmentary left end elevation of parts shown in Figures 1 and 5.

Figure 9 is a detail sectional view on line 9—9 of Figure 8.

Figure 10 is a detail sectional view on line 10—10 of Figure 9.

Figure 11 is a diagrammatic view showing the control and actuating mechanism in position for rough grinding and with the wheel traversing to the left.

Figure 11a is a fragmentary top plan showing a control member.

Figure 12 is a view similar to Figure 11, but showing the parts in dress position between rough and finish grinding.

Figure 13 is a view similar to Figures 11 and 12, but showing the parts in final grinding position traversing to the left.

Figure 14 is a diagram showing the parts in final fast traverse position.

2

Figure 15 is a view similar to portions of Figures 11 to 13 but with the parts shown in position for traverse of the wheel to the right.

Figure 16 is an elevation of an electrically actuated switch shown diagrammatically in Figures 11 to 14, inclusive.

Referring first to Figures 1, 2 and 3, the machine as shown is an internal grinding machine. This machine is provided with a bed 1 having 10 mounted at the left hand end thereon a work holder carriage 2. This work holder carriage carries thereon a head 3 which is angularly adjustable along curved ways 4. It supports a rotary work spindle carrying at its right hand 15 end a suitable work holding chuck 5, and at its left end pulleys 6 and 7. Either selected of these pulleys may be connected as by the V-belts 8 to a corresponding pulley 9 or 10 on the shaft of a motor indicated generally at 11, this motor providing means for rotating the work carried by the chuck 5 and indicated generally at 12. This work holder 2 is mounted for sliding motion from front to back, thus providing for a feed motion between the wheel and the work. The 20 feed mechanism will be further described.

To the right of the work holder 2 is mounted a wheel carriage 15 rotatably supporting a spindle 16 carrying a wheel shaft 17 at the end of which is carried the grinding wheel 18. This wheel carriage is fixed to a tubular member 20 (see Figure 3) which is rockably and axially movable on arcuate bearing members, one of which is shown at 21a in Figure 3. The member 20 is formed with a central partition 21 as shown best in Figure 11, and forms a pair of axially aligned cylinders receiving through their outer ends a pair of tubes 22 through which fluid may be passed into or discharged from the respective cylinders through the pipes 23 and 24, thus to produce axial reciprocation of the member 20, and with it, a corresponding motion of the wheel carriage 15. This motion of the wheel carriage produces the desired traverse of the work by the grinding wheel during the grinding operation, 35 as well understood in the art.

Feed mechanism

As before noted the feed between the work and the wheel is produced by motion of the work 40 transverse to the traverse direction. Referring to Figure 3, the work carriage 2 has a bracket 25 secured to a depending front apron portion 26 as by screws 27. This bracket has journaled therein a feed shaft 28. The rear or inner end of this 45 feed shaft is formed as a feed screw 30 which is

threaded through a nut 31 mounted for rotation in a sleeve 32 of a bearing 33 carried by the base 1 of the machine. It will be evident that feed may be produced either by rotating the shaft 28 or by rotating the nut 31.

Rotation of the shaft 28 may be produced by rotation of a hand wheel 29 having a hub portion 290 secured to the shaft 28, as by means of a nut 291 engaging a threaded extremity of the shaft 28. Shaft 28 may also be rotated by the rotation of a gear ring 34 secured to the hub portion 290 as by screws 35. This gear ring 34 acts as a worm wheel and may have engaged therewith a worm 37 keyed to a shaft 38 to the outer end of which is keyed a suitable hand knob 39 by which it may be turned as shown in Figure 4. This shaft 38 is journaled eccentrically in a bushing 40 having a hub 41 to which is secured a handle 42. By turning this bushing 40 to bring its handle 42 between the full line position and the dotted line position of Figure 4, the shaft 38 is lifted bodily so as to lift the worm 37 out of contact with the gear ring 34. In this position the shaft 28 may be turned freely by rotation of the hand wheel 29. In the full line position shown in Figure 4, the engagement of the worm 37 with the gear 34 locks the shaft 28 against turning by rotation of the hand wheel 29 but permits a very slow rotation to be imparted thereto by rotation of the hand knob 39. This mechanism provides an operator actuatable mechanism for determining the initial feed position as when setting up the machine.

The feed may then be effected by power in accordance with the predetermined cycle of the machine. This power feed is produced by rotation of the nut 31 for which purpose there is secured thereto, as by screws 45, a ring gear 46. This ring gear projects through an opening 47 in the top wall of the bed 1 and meshes with a gear 48 having a hub portion 49 journaled on a bushing 50 carried by a stud shaft 51 secured to a bracket 52 as shown in Figures 3 and 5. This bracket 52 is secured to a partition member 53 of the base 1 as by screws 54. The hub 49 is provided with an integral worm wheel portion 56, which as shown best in Figure 5, meshes with the threads on an externally threaded quill 58. This quill forms the piston rod of a power feed cylinder 60, the quill having an enlarged diameter portion 61 fitting within the cylinder 60 and a somewhat smaller diameter extension 62, which is guided through the cylinder head 63. The cylinder 60 and its head 63 are fixed to the feed bracket 52 as by screws 64. The quill 58 is mounted for both axial and rotary motion within the cylinder 60 and when moved axially its threads act as a rack in engagement with the teeth of the worm gear 56. This axial motion of the quill produces the normal feed motion of the work relative to the wheel, while rotary motion of the quill produces a slow additional feed motion, which is for the purpose of compensating for wheel wear and truing.

Rotation of the quill 58 may be produced by rotation of a splined shaft 65, the splined portion of which extends into an enlarged bore 66 of the quill. This shaft 65 is journaled in a bearing 68 and just rearwardly of this bearing it is provided with the outer or cup member 70 (see Figures 5 and 6) of a one direction roll clutch device. The inner member 71 of this clutch device is carried by a shaft 72 and between these elements and seated in inclined recesses in the inner clutch element 71 are the clutch balls 73. Rotation of the shaft 72 in one direction, therefore, serves to rotate the splined shaft 65 and through it the

quill 58, thus to produce as low rotation of the worm wheel 56, while rotation of the shaft 72 in the opposite direction is ineffective to transmit turning motion to the quill.

The shaft 65 may also be locked against rotation, except when it is desired to turn it. This may be produced by forming the outer periphery of the cup element 70 with serrations into which may be projected the edge of a locking bolt 75 (see Figures 5 and 6). This locking bolt may have a head 76 riding in a fluid pressure cylinder 77 and may be normally pressed into locking engagement with the cup element 70 as by a spring 78. A screw 79 extending through the cylinder wall and engaging in a slot 80 in the head 76 prevents the locking bolt 75 from being turned out of position to properly register with the serrations of the element 70. This locking bolt may be retracted by fluid pressure admitted above the head 76 as through a pipe 81. Retraction of the locking bolt 75 opens a port leading to a pipe 82 from which fluid pressure may be led to a mechanism for rotating the shaft 65.

Fluid pressure mechanism for rotating the shaft 65 is shown best in Figure 7. The rear end of the shaft 72 has fixed thereto a pinion 85 with which meshes rack teeth on a cylindrical rack bar 86. This rack bar forms the plunger of a hydraulic cylinder 87 and is provided with a head 88 at its inner end which may abut against an adjusting stop screw 89 threaded through the head 90 of a hydraulic cylinder. The plunger is normally held in this position as by means of a coil spring 93 seated in a socket 91 in the outer end of the plunger engaging over a centering pin 92 carried by the fixed frame member 53. The pipe 82 permits fluid under pressure to be introduced into the pressure cylinder 87, this acting to force the plunger 86 outwardly to rotate the pinion 85 in one direction, while when the fluid under pressure is permitted to discharge through the pipe 82, the spring 93 forces the plunger back and turns the gear 85 in the opposite direction. A check valve 95 (Figures 11 to 14) prevents the fluid under pressure from reaching the cylinder 87 from the pipe 81 so that the latch bolt has to be first released, opening the pipe 82. The direction of motion produced by the fluid under pressure is such as to rotate the shaft 72 in the direction to turn the splined shaft 65 and thereby rotate the quill 58.

As before noted, the axial motion of the quill 58 produces the normal feed motion of the work carriage, and this feed is produced by motion of the quill to the left from the position shown in Figure 5. Its limit of motion is determined by either of a pair of switch actuating stops 100 and 101 which are mounted for sliding motion through a plunger 102. This plunger is supported adjacent to opposite ends in cylindrical guide members 103 and 104. The guide member 103 is provided with a key way 105 for the reception of a key 106 carried by the plunger 102 and by which this plunger 102 is prevented from turning. The plunger 102 is normally urged toward the position shown in Figures 5, 9, 12 and 13 as by a spring 107 seated in a socket 108 in one end of the plunger and reacting against a head plate 109 bridging across the cylindrical bore of the guide member 103 and fixed as by the screws 110. The bore of the guide member 104 forms a hydraulic cylinder closed off at its outer end by a cover plate 115 secured in position as by the screws 116, and through this cover plate extends a hydraulic pipe 118 through which fluid under

pressure may be passed to force the plunger 102 against the pressure of the spring 107 to the position shown in Figures 11 and 14. In the position shown in Figures 5, 9, 12 and 13, the stop 100 is positioned opposite to a plug 120 secured in the outer end of the quill 58, while when the plunger 102 is in the position shown in Figures 11 and 14 the stop 101 rather than the stop 100 is in alignment with the plug 120.

The stops 100 and 101, as shown, are identical in construction. Referring to Figure 9, each stop comprises a screw 125 having a head 126 which facilitates turning it for adjustment, this screw having threaded engagement in a sleeve 127 which is slidably keyed in a bore 128 of the plunger 102. At its inner end this sleeve 127 has an enlarged head 130 with an enlarged diameter flange 131. Between this flange and a counterbored portion 132 of the bore of the plunger 102 is positioned a coil spring 133 which acts to hold the stop projected toward the plug 120 as far as is permitted by a collar 135 threaded onto a portion of the sleeve 127 and secured in adjusted position thereon as by a set screw 136. By turning the screw 125 the amount by which it projects beyond the head 130 may be adjusted, and it may be fixed in such adjusted position as by a lock nut 140 threaded thereon and bearing against the rear extremity of the sleeve 127. It will thus be seen that the stops are individually adjustable axially and as shown one of these, the stop 101, is adjusted further inwardly than the stop 100. This stop 101 limits the extent of feed for a rough grinding operation and this limit, of course, should be somewhat short of the full depth of cut. The stop 100 is set for the final work dimension as the result of a finishing cut and is therefore retracted by the amount required for the finishing cut over the position of the stop 101.

The axial motion permitted these stops is made use of to actuate a pair of controlling electric switches shown at 145 and 146 (see Figures 8, 9 and 10) and these are actuated simultaneously by the rocking of a lever plate 147 journaled between two cone centers 148 and 149 carried by a forked supporting plate 150 secured to a bracket 151 (see Figure 10) as by the screws 152. One end of the plate 147, as at 155, projects sufficiently toward the stops so that it may be engaged by either of the collars 135 which happens to be opposite thereto, depending on the axial position of the plunger 102, so that when the stop engaged by the plug 120 of the quill is pushed outwardly thereby, the lever 147 is rocked from the position shown in Figure 10 until it contacts and depresses the two push button switches 145 and 146. This lever plate 147 is normally held away from the push button switches as by a leaf spring 156 and in contact with a stop pin 157. The functions of the switches 145 and 146 will be later explained.

While the feed is taking place there is also effected a traverse of the wheel relative to the work. This is done automatically and during the normal grinding operation the traverse is produced through an amplitude of definite length. As will later appear, after the rough grinding has been effected, the machine is conditioned automatically for an extended traverse of the wheel in one direction which brings it away from the work, and during this extended traverse the wheel is trued. The machine is then automatically conditioned to return to the grinding cycle to effect finish grinding within the normal grind-

ing traverse limits and the stop plunger is moved to present the finish grinding stop into operative position. The feed is resumed and when the desired finish size is ground, the grinding cycle stops with the wheel at a further extended traverse limit away from the work, whereupon the ground work may be removed and an unground piece substituted therefor. The cycle of grinding for the new piece may then be initiated by the operator.

Traverse mechanism

As shown the means for producing traverse of the work carriage is hydraulic, the control being through a plurality of valves, some of which are controlled by electrical circuits as will later appear. Movable with the tubular member 20, and thus with the wheel carriage, is a support 200 having a plurality of longitudinal grooves therein along which may be adjustably fixed stops 201, 202 and 203. The stop 201 is longer than the stops 202 and 203 and determines the limit of stroke of the wheel carriage inwardly. The stop 202 is the shortest of the three and determines the outer limit of traversing motion during the normal grinding operation only. The stop 203 is intermediate in length between the stops 201 and 202 and determines the outward limit of extended traverse during which the wheel is dressed. Another limit of outward motion at which the finished work is removed and new work to be ground inserted is determined by the maximum travel of the wheel slide which is reached when the partition 21 contacts with the end of the member 22.

The determination of which of these stops is effective at any time is effected by the axial position of a control member 204 which may be moved axially by hydraulic means and is also permitted a rocking motion. The rocking motion acts to reverse the direction of traverse at the desired traverse limits. Eccentric to this member 204 is a post 205 projecting therefrom which may be struck by the stops 202 or 203 as the wheel carriage traverses, depending on the axial position of the member 204, to rock the member 204 in one direction, while contact of the stop 201 with the post 205 or on a cutaway edge of the collar portion 206 of the member 204 (see Figure 11a) acts to rock the member 204 in the opposite direction. This general arrangement per se with the three stops and a rockable and axially movable control member is not per se my invention, but the construction of the member 204 and associated parts and its hydraulic control does form a portion thereof. This member 204 is rockably carried by a yoke 208, but is connected for axial motion therewith. This may be produced by providing the yoke member 208 with a shaft extension 209 having a peripheral groove 210 therein, this shaft extension being rotatable within a socket 211 in the lower end of the member 204. Any suitable means, such as a set screw 212 having its inner end riding in the peripheral groove 210, may be employed to retain the yoke and member 204 in assembled relation for simultaneous axial motion but with capability of relative rotation. The yoke member 208 has a central plunger portion 214 which projects into a casing 215 within which is slidably a cup member 216 having a shank portion 217. This shank portion projects through the lower end of the casing 215 and through it extends a port 218 connecting with a pressure supply and discharge pipe 219. A similar pipe 220 passes through the wall of the casing 215 and opens up beneath the cup-shaped

portion 216 outwardly of its shank 217. When fluid pressure is admitted through the passage 218, the plunger 214 is lifted to its top position as shown in Figure 11, at which time the element 205 is in position to contact the stop 202, while either the element 205 or the cut away portion of the flange 206 remains in all of the axial positions of member 204 in position to be contacted by the stop 201. If the fluid pressure is not admitted through the pipe 219 and the port 218, the plunger 214 may descend to the bottom of the cup 216, and where this cup 216 is in its lowered position as shown in Figure 11, the member 214 is then in its lowest position as shown in Figure 14. In this position the element 205 is too low to be contacted by either of the stops 202 and 203 and the grinding wheel carriage can then make its full stroke away from the stop 201 to the work loading and unloading position. When fluid pressure is introduced through the pipe 220 beneath the cup member 216, this cup member is lifted to its upper position shown in Figure 12 and with the member 204 in a position which is intermediate to its top and bottom positions and in which it may be contacted by the stop 203, but is too low to be contacted by the stop 202. The grinding wheel may then take its extended traverse for truing.

It will be noted that when contact is made on the member 204 with any of the stops, it is turned angularly first in one and then in the other direction. This turning causes reversal of the direction of traverse of the wheel carriage. To this end a portion of the length of the member 204 on its back face is provided with gear teeth which mesh with teeth of a rack bar 225. This rack bar is a part of or forms an extension to a pilot valve 226, and rocking of the member 204 from one to the other of its positions changes the axial position of the pilot valve 226 between the positions shown in Figures 11 and 15.

Referring first to Figure 11, a liquid suitable for a hydraulic system, such as oil, is pumped from the supply reservoir 230 by the pump 231 into a pipe 232. A pressure relief valve at 233 connected to the pipe 232 and leading back to the tank 230 limits the pressure of the liquid in the pressure pipe 232. This pipe 232 leads to a valve casing 234 having within it a reciprocable reversing valve 235. In the position shown in Figure 11, the reversing valve is at the right hand end of its cylinder, opening communication from the pressure pipe 232, around the neck 236 of the reversing valve, through the pipe 237 to the casing 238 of the pilot valve, around the neck 239 of this pilot valve and into an axial passage 240 therein, and out around the neck 241 of this pilot valve through the pipes 242, 2420 to the left hand end of the reversing valve, thus retaining the reversing valve in the position shown. The fluid under pressure also passes around the neck portion 236 of the reversing valve through the pipe 23 and the member 22 into the right hand end of the cylinder 20, thus to move this cylinder and the wheel carriage to the left. At the same time liquid is escaping from the left hand end of the cylinder 20 through the pipe 24, around the neck 245 of the reversing valve, pipe 246, to the pilot valve, around the neck 247 of this pilot valve and through the pipe 248 to the valve casing 249 within which is axially slid able the valve 250 fixed to one arm of the yoke 208, the discharge passage around a neck 251 of this valve, through the pipes 252 and 2520, through the throttle valves 253 and 2530, and the pipe 254 to the discharge pipe 255, 75

which leads back to the supply tank 230. The setting of the valves 253 and 2530 determines the speed of traverse since they determine the rate of discharge from the left hand side of the cylinder 20. The discharge from the right hand end of the reversing valve 235 takes place, first through the pipes 260 and 261, around the neck 262 of the pilot valve, through the central passage 263, around the neck 264 of the pilot valve, and out through the discharge line 255. After the pipe 260 has been closed by the reversing valve as shown in Figure 11, discharge continues to take place through the pipe 261 at the end of the valve at a reduced rate of speed until the valve is in its extreme right hand position shown. This arrangement of the two end pipes 260, 261 and 242 and 2420 leading from the reversing valve, one of which is shut off before the other one, provides for the slowing down of the travel of the reversing valve adjacent to the ends of its stroke and this with the tapered end of the valve head 2360, for a dwell in the motion of the wheel slide. When the member 204 is turned by impingement of the member 201 thereon, the pivot valve 226 then takes the position of Figure 15. In this position pressure from the pressure pipe 232 passing to the reversing valve casing 235 with the reversing valve in the position of Figure 11, passes around the neck 236 of this reversing valve, through the pipe 237 to the pilot valve, around the neck 239 of this pilot valve, as shown in Figure 15, through the axial passage 265 to the pipes 261 and 260, while the pipes 242 and 2420 at the left hand end of the reversing valve are connected around the neck 270 of the pilot valve through the axial passage 271, and the neck 272 of the pilot valve to the discharge pipe 255. Thus the reversing valve is pushed to its left hand position shown in Figure 15 where the pressure pipe 232 is connected around the neck 245 of this valve to the pipe 24 leading to the left hand end of the cylinder 20, while the pipe 23 is connected around the neck 236 of the reversing valve and the pipe 237, around the neck 247 of the pilot valve, and to discharge through the pipe 248, as previously described. The direction of carriage travel is thus reversed. On turning of the member 204 back to its original position so that the pilot valve 226 is in the position shown in Figure 11, and the pilot valve is in the position shown in Figure 15, the pressure connections to the pilot valve and to the reversing valve through the pilot valve are as previously described, causing the reversing valve to be moved to the position of Figure 11, and reversing the pressure and discharge passages with respect to the ends of the cylinder 20. This action of reversing takes place regardless of the axial position of the member 204, so long as there is some means for turning the member 204.

At the end of the cycle of operations where the member 204 is too low to be contacted by either of the stops 202 or 203, and the carriage proceeds to its extreme outward limit of motion, where it stops for loading and unloading, there is nothing to turn the member 204 to effect reversal, hence the machine stops at this position. When it is desired to start it again, the operator turns the member 204 by hand as by means of the handle 275, whereupon the traverse commences, the member 204 being lifted first to its uppermost position by mechanism which will later be described.

Cycle control mechanism

Besides carrying the valve 250, the yoke 208

also carries another valve 280 having a pair of necks 281 and 282 and this valve forms part of the mechanism which controls the feed motion of the work carriage which is operated from a pressure circuit independent of that which operates the wheel traverse.

The axial position of the member 204 is determined by the pressure circuit which operates the traverse, through electrically controlled valves A and B. The wheel feed and retraction is controlled by electrically actuated valves C and D, while the positioning of the rough grinding and finish grinding stops is controlled by the electrically operated valves E and F. All of these valves A, B, C, D, E, and F are of the same construction, each being provided with a single neck between two heads, and each controlling connections between a single pipe on one side and two pipes on the other so as to connect the two pipes alternately to the single pipe, depending upon the valve position. Each of these valves is normally held in one axial position, but is adapted to be moved to the other axial position by energization of an actuating coil A', B', C', D', E', and F', respectively, and these are controlled partly by the switches 145 and 146, three relays 300, 301, and 302 and two motor actuated switches 303 and 304. Each of the motor actuated switches 303 and 304 is of the type shown in Figure 16, in which energization of a motor 305 rotates a cam 306. The rotation of this cam 306, acting upon a follower lever 307, first closes contacts at 308 and 309, as soon as this rotation has been permitted by the release of a latch member 310 from a notch 3100 in a disk 317 rotatable with the cam 306, by energization of the solenoid 311. Such energization pulls backwardly on a hook 312 which engages the lower end of the latch 310 and also closes contacts at 313 and 314 which complete the circuit to the motor 305 through a lead 315 in parallel with the solenoid 311, starting rotation of the motor. The solenoid 311 retracts the hook 312 until it snaps out of contact with the latch 310 which then rides on the surface of the disk 317 rotatable with the cam 306 and holds the motor control contacts 313 and 314 closed until the cam has made a complete revolution, whereupon the latch snaps back into the notch 3100, opening the contacts 313 and 314, stopping further rotation of the motor 305, and permitting the hook 312 on de-energization of the solenoid 311 to be brought back by a spring into catching relation with the latch 310, the hook yielding to pass beneath the latch 310 and engage its forward face. The action of each of the switches 303 and 304 is therefore to close a circuit for a short time and then after a predetermined interval to open it again, the opening taking place when the cam 306 permits the follower portion 307 to break the contacts at 309.

Each of the relays 300, 301 and 302 take either of two positions, each having a pair of spaced solenoids with an armature therebetween, the armature being attracted to one or the other of the solenoids, depending upon which one is energized at a particular time, and the position of the armature defining the position of a plurality of pivotally mounted switch arms. As shown each of these armatures is one arm of a bell crank lever, the other arm of which is connected to a rod pivotally connected to the various switch arms controlled thereby, spaced from their pivots.

The relay 300 is provided with an armature 320

which is connected through the rod 321 with the switch arms 322, 323, 324 and 325, and it has the actuating solenoids 326 and 327. The switch 301 is provided with an armature 330 which actuates the switch rod 331 controlling the switch arms 332, 333, 334 and 335, and is provided with the actuating solenoids 336 and 337. The relay 302 is provided with an armature 340 which actuates the switch controlling rod 341 controlling the positions of the switch arms 342 and 343, and it is provided with the actuating solenoids 344 and 345.

In the position of the parts shown in Figure 11 during an intermediate portion of the rough grinding, the valve coils A' and E' are energized, while the valve coils B', C', D' and F' are not energized. The valve A is then in position for fluid pressure from the pressure line 232 to reach this valve through the pipe 350, to pass around the neck 351 of this valve, and through the pipe 216 into the cup member 216 beneath the plunger 214, thus holding the member 204 in its highest position where it is in position to be impinged upon on opposite ends of its traverse by the stops 202 and 201, thus to produce the relative short working traverse of the wheel carriage. This energization of the valve coil A' is produced from the power lines 355 and 356 through the lead 351 from the line 355, the coil A', lead 358, contact 359; switch arm 325 of relay 300, and lead 360 to the line 356. The feed stop carrying member 102 is at its uppermost position with the feed stop 101 for rough grinding in alignment with the quill 58, this being accomplished by the energization of the valve solenoid E', which receives fluid under pressure from a pressure pump 365, drawing from the supply tank 230, through a pressure pipe 366 in which the pressure is limited by the pressure relief valve 365 discharging back into the supply tank 230, through pipes 367 and 368 to the valve E, around the neck 359 of this valve, and through the pipe 310 to the lower end of the member 102. As before noted, this upper position of the member 204 holds the valve member 250 in its uppermost position wherein the discharge of fluid from the traversing cylinder for both directions of traverse takes place through the throttle valves 253 and 2530, thereby holding the speed of traverse to the desired low value. In the same position of the member 204 and during grinding, the valve member 280 is in its uppermost position in which fluid under pressure from the pressure pipe 366 reaching the valve 281 passes around the neck 282 of this valve and through the pipe 371 to the right hand end of the feed cylinder 60, while the fluid under pressure is discharged from the left hand end of this cylinder through the pipe 372, around the neck 281 of the valve 280, through the pipe 373, around the neck 374 of the valve C, through the pipe 375, around the neck 376 of the valve D, through the pipe 377 and the throttle valve 378 to the discharge pipe 379, which leads back to the supply tank 230. The speed of feed is thus governed by the setting of the throttle valve 378.

It is desirable in the retracted relative positions of the wheel and work, that the wheel be spaced somewhat from the work in order to fully clear it. In order to save time it is therefore desirable to feed the wheel and work relatively from the wheel retracted position quickly to bring the wheel up close to the work and thereafter to produce feed at the slower normal speed proper for cutting. Means to provide this initial relatively

quick feed comprise the hydraulic valve C with associated parts and its controlling switch 304. In the position of the relay 300 shown in Figure 11, the switch arm 324 is closed, closing a circuit from the line 356 through lead 360, switch arm 324, lead 3040, the solenoid 311 and then the motor of the switch 304 and lead 3042 to line 355. This acts immediately to close and hold closed but for only a limited time the switch arm 3041, which closes a circuit from line 356 through leads 414, 3043, switch arm 3041, lead 3044, solenoid C' and lead 3045 to line 355. This moves the valve C to a position where discharge from pipe 373 passes around the neck of valve C, through the pipe 3740 to the discharge pipe 379, cutting out the restricted discharge through pipe 375 past the valve D and through the throttle valve 387. As soon as the motor of switch 304 allows the switch arm 3042 to open, the valve solenoid C' becomes de-energized, and the valve C returns to its upward position as shown, the initial rapid feed having already been completed, whereupon the unrestricted discharge is cut off and the discharge throttled by the valve 378. Further feed during the rough grinding then proceeds slowly after the rapid initial feed which brings the work and wheel close together. The switch 304 with its motor drive is thus a timing device controlling the time of the rapid initial idle feed between the work and wheel which brings them close to each other before the slow working feed is thrown in. The slow feed is thus in action when the wheel and work contact and during the entire time of grinding. The slow grinding feed continues, the wheel traversing the work and being gradually fed into the work until the feed sleeve 58 through its plug 120 contacts the stop 101 which it pushes outwardly against the lever 141 (see Figure 10) until it closes both of the switches 145 and 146.

The closing of the switch 145 closes a circuit from the line 355, through leads 380, 381, switch 145, lead 382, solenoid 327 of the relay 300, lead 383, switch arm 323 of relay 300, lead 360 back to the line 356. This moves the armature 320 over to the solenoid 327, and in doing this it breaks the connection between the switch arm 323 and the lead 383, thus immediately de-energizing the solenoid 327, the relay 300 then being in the position shown in Figure 12. The closing of the switch 146 acts to close a circuit from the line 356 through the leads 385 and 386, switch 146, lead 387, switch arm 343, lead 388, solenoid 337 of the switch 301, lead 389, switch arm 332 and lead 390, back to the line 355. This immediately throws the armature 330 over toward the solenoid 327, which immediately breaks the contact between the switch arm 332 and the lead 389, thus opening the circuit through the solenoid 337, but leaving the switch 301 in the condition shown in Figure 12. It will thus be seen that the relays 300 and 301 have been thrown to their opposite positions from the showing of Figure 11 to the showing of Figure 12, but for the present the relay 302 remains in the position of Figure 11.

With the switches 300 and 301 in the position of Figure 12, the solenoid A' has been de-energized through the breaking of the contact between the switch arm 325 of relay 300 and the lead 359 so that the valve A takes its other position. This connects the pipe 219 around the valve neck 351 of the valve A, through the pipe 391 to the discharge pipe 255, so that the plunger 214 descends to the bottom of the cup member

216. However, the valve coil B' is now energized by closing of the switch arm 325 to the lead 421, which completes the circuit from the line 356, lead 360, switch arm 325, lead 421, coil B', lead 420, switch arm 335, lead 390 to line 355 so that pressure from the pressure pipe 350 passes around the neck 393 of valve B through the pipe 220, beneath the cup member 216, thus raising this cup member, together with the plunger 214. The reversal of the positions of the relays 300 and 301 thus acts to lower the member 204 one step to its truing position as shown in Figure 12. This lowering of the member 204 lowers the valve 280 from the position shown in Figure 11 to that shown in Figure 12, reversing the connections from the fluid pressure line 366, so that pressure now flows through the line 372 to the left hand end of the feed cylinder 60 and connects the pipe 371 from the right hand end of the feed cylinder to around neck 282 of the valve 280 through the pipe 3730 to the discharge pipe 373. This discharge is unrestricted so that the feed quill is returned quickly to its starting position. In this position of the member 204, also, the valve 250 has moved from the position in Figure 11 to the position shown in Figure 12, so that the discharge of fluid from the pilot valve casing through the pipe 248 no longer takes place through both of the throttle valves 253 and 2530, the pipe 2520 having been blanked by the valve 250, but takes place through the single throttle valve 253 so that the speed of traverse is reduced, at which time the stop 202 is no longer effective to reverse the direction of traverse so that the wheel slide is given an extended traverse until the stop 203 is effective, and during this extended traverse the wheel is automatically trued. The pressure from this pipe 220 also flows through a pipe 394 to a cylinder 395 of a wheel truing device 396 (shown best in Figure 1a), passing to the left of a piston 397 whose piston rod is connected to one arm 392 of a bell crank lever, the other arm of which carries the truing diamond. A spring 398 engaging the back face of the piston 397 holds the bell crank lever tilted with the truing device at the inoperative position except when pressure is applied to the cylinder 395 through the pipe 220. This inoperative position is shown in full lines in Figure 1a and Figures 11, 13 and 14. This truing device is positioned as shown in Figures 1 and 2 beyond the end of the work, where when the truing device is in operative position, it will be engaged by the grinding wheel during its extended traverse, thus to true the wheel.

The throwing of the relay 301 from the position shown in Figure 11 to that shown in Figure 12 closed the switch arm 334 to the lead 408 which established a circuit from the line 355, lead 390, switch arm 334, lead 408 and 409, to the motor of the switch 303 and lead 410 to the line 356. This, as before noted, closed for a short period the switch arm 415 which established a circuit from the line 355 through the leads 380 and 412, solenoid F', lead 413, switch arm 415, lead 414 to the line 356. Energization of the solenoid F' pulled the valve F downward for a short period of time and in this downward position, fluid from the pressure line 366 and pipes 367 and 368 passing the neck of this valve flowed into the pipe 81 which acted to pull the latch 75 into unlocking position and thereafter to force the plunger 88 inwardly from the position shown in Figure 7 to impart rotation to the gear 85 the extent of which was determined by the setting of the stop 89 shown in Figure 7, thus turning the splined shaft 75

13:

65 and the quill 58, thus giving a small feeding motion to the work carriage which supports the truing device so as to advance the truing device for the truing action. As soon as the motor of the switch 303 completed its cycle of operations, the switch arm 415 returned to its open position, the solenoid E' was de-energized, and the pipe 81 was disconnected from the pressure pipe 368 and connected to the discharge pipe 379, thus permitting the return of the feed plunger 83 and the latch block 75 to their former positions under the influence of their respective springs.

As the grinding wheel returns from this extended portion of its traverse during which it was trued, past the stop 202, a dog 400 carried by the wheel carriage passes by and momentarily closes a switch 401. It will be noted that the dog 400 is ineffective to close the switch 401 during the outward traverse of the wheel carriage, this dog being so mounted as to yield against the action of a spring when it strikes the non-beveled face of the switch 401. Closing of the switch 401, closes a circuit from the line 356 through the lead 385, switch 401, lead 402, lead 450, switch arm 322 of relay 300, through the left hand solenoid 326 of the relay 300, lead 451, back to the line 355. This causes the left hand solenoid 326 of the relay 300 to be energized, throwing the relay from the position shown in Figure 12 to the position shown in Figures 11 and 13, the other relays 301 and 302 remaining as before, all the relays therefore being in the relationship shown in Figure 13. This change in the position of the armature 320 of the relay 300, closes the switch arm 325 to the lead 359 and opens it with respect to the lead 421. By opening the connection to the lead 421, the valve solenoid B' is de-energized, permitting this valve to move from the position shown in Figure 12 to the position shown in Figures 11 and 13. Closing of the connection between the switch arm 325 and the lead 359 again energizes the valve solenoid A'. The motion of the valve B when its coil B' is de-energized, closes off the pipe 220 from the pressure line 350 and connects it to the discharge line 392. Fluid under pressure is thus discharged from beneath the cup element 216. The energization of the solenoid A', however, opens communication from the pressure line 350 to the line 219 leading to the interior of the cup member 216, this lifting the plunger 214 to its uppermost position shown in Figures 11 and 13, so that the member 204 is again in grinding position, and in the same position as during the rough grinding operation shown in Figure 11. The throwing of the relay 300 to the position of Figure 13 also closing the switch arm 324 to the leads 3940, establishes connection from the line 356, through lead 369, switch arm 324, lead 3940 to the motor of the switch 304, which as noted previously in connection with the description of the rough grinding operation, acts for a short interval to close the switch arm 3043, energizing the solenoid C' and moving the valve C for a moment to the position where free discharge from the left hand end of the cylinder 60 through the pipe 372 is afforded, thus to provide a quick feed to bring the work and wheel close together, after which on deenergization of the solenoid C', the discharge from the left hand end of the cylinder 60 is controlled by the valve D through energization of its solenoid D' to take place through the throttle valve 452. It will be noted that this valve 452 is a different valve from that through which the discharge is effected during

14:

the grinding operation shown in Figure 11, in which the solenoid D' was not energized, the slow discharge at that time taking place through the throttle valve 373. The throttle valve 452 may be set for a slower discharge than valve 373, so that the finish feed is slower than the rough grinding feed. The solenoid D' is energized from the line 355 through lead 390, switch arm 334 of the relay 304, leads 408, solenoid D', and lead 422 to the line 356. It will also be noted that in this position of the relay 304, the solenoid E' for the valve E has been de-energized, due to the breaking of the contact between the switch arm 334 and the lead 460 leading to the solenoid E'. This positions the valve E so as to connect the pipe 370 to the discharge pipe 379 so that the member 102 has dropped to the position shown in Figures 12 and 13, so that the stop 104 is no longer in alignment with the plug 120 of the feed quill 58, but the finish stop permits a greater amount of feed than the rough grinding stop 101, thus to provide for the amount of stock to be removed in the finish grinding operation. The traverse and slow working feed then continues with the parts shown in the position of Figure 13 until the plug 120 contacts with the stop 100 and closes the switches 145 and 146.

30. The closing of the switch 145 establishes a circuit from the line 356, lead 360, switch arm 323, through the right hand solenoid 327 of the relay 300, lead 382, switch 145, leads 384, and 380, to the line 355. This throws the relay 300 to the position shown in Figures 12 and 14. This opens the connection between the switch arm 325 and the lead 359, de-energizing the solenoid A' and permitting the valve A to assume the position shown in Figures 12 and 14, this, as previously described, opening the pipe 219 leading from beneath the plunger 214 to discharge through the pipes 391 and 355. This permits the plunger 214 to descend to the bottom of the cup member 216. The closing of the switch 146 also establishes an electric connection from the line 356, through leads 385 and 386, switch 146, lead 387, switch arm 343 of the relay 302, lead 381, left hand solenoid 336 of the relay 301, switch arm 332 and lead 390 to line 355, which throws the relay 301 into the position shown in Figure 14. This breaks the connection between the switch arm 335 of the relay 301 to the lead 420, thus breaking the circuit through the solenoid B', allowing the valve B to take the position shown in Figures 11 and 14 where the pipe 220 leading from beneath the cup member 216 is open to the discharge pipe 392. Thus the cup member descends so that the member 204 takes its lowest position, as shown in Figure 14, where its element 205 may strike the stop 201 at the inward limit of traverse, but where at the outward limit of traverse it passes the stops 202 and 203 and finally comes to rest at the extreme limit of its stroke without the member 204 having been turned to reverse the direction of traverse. Since the truing device is also connected to the pipe 220 which is being discharged, at this final outward motion of the traverse, the truing device is out of operative position and is therefore ineffective to true the wheel. In this lowest position of the member 204, the valves 250 and 280 are in the position shown in Figure 14 where the pipe 372 is open to discharge through pipes 3730 and 379 while the pipe 371 is open to pressure through the pressure pipe 366. The feed quill 58 is then in re-

tracted position, while the pipe 248 leading from the pilot valve casing is connected directly to discharge through the pipes 465 and 355. As there is no throttle valve in this discharge path, the final outward traverse is at a rapid rate.

The finished ground work may then be removed from the machine and new work placed in position therein. The machine may then be started by turning the member 204 by hand, as by operation of the handle 205, to start the inward traverse. As the dog 400 passes beneath the switch 401 on this inward traverse it closes this switch, re-establishing a circuit between the leads 402 and 325. This completes the circuit from the line 356 through lead 385, switch 401, leads 402 and 450, switch arm 322, left hand solenoid 326 of the relay 303, lead 451, to the line 355. It also establishes a connection from the lead 402, through the switch arm 342 of relay 302, the left hand solenoid 344 of this relay, lead 471, switch arm 333 of relay 301, and lead 360 to line 355. This acts to return the relays 300 and 302 to the positions shown in Figure 11, thus automatically conditioning the machine for the rough grinding operation as previously described between the stop limits 201 and 202, lifting the member 204 to its grind position, giving a fast and then a slower machine feed, and lifting the stop carrying member 102 to position the rough grinding stop 101 into alignment with the plug 120 and the machine repeats its cycle.

From the foregoing description of an embodiment of this invention, it should be evident to those skilled in the art that various changes and modifications might be made without departing from the spirit or scope of this invention.

I claim:

1. A carriage moving means including a rotary shaft, connections from said shaft to said carriage causing rotation of said shaft to move said carriage, a gear fixed to said shaft, an externally threaded quill engaging the teeth of said gear and mounted for axial and rotational motion, the threads of said quill acting as a rack with respect to the teeth of said gear on axial motion of said quill and as a worm on rotation of said quill, a rotary shaft splined to said quill, means for moving said quill axially to impart a relatively rapid rotation to said rotary shaft, and means for rotating said splined shaft to impart a relatively slow rotation to said first mentioned rotary shaft.

2. A carriage moving means including a rotary shaft, connections from said shaft to said carriage causing rotation of said shaft to move said carriage, a gear fixed to said shaft, an externally threaded quill engaging the teeth of said gear, said quill having a piston portion, a fluid pressure cylinder within which said piston and quill may move axially and rotate, fluid pressure means communicating with said cylinder for moving said quill axially, said quill then acting as a rack with respect to said gear, a shaft splined to said quill, and means for rotating said splined shaft, said quill acting as a worm with respect to said gear on rotation of said quill.

3. A grinding machine having a work holder, a grinding wheel carriage, means for relatively moving said holder and carriage in a direction to feed a grinding wheel on said carriage relative to work on said holder, said moving means comprising a one direction driving clutch, an oscillatory shaft for driving said clutch, a fluid pressure actuated plunger connected to said shaft to rock said shaft in opposite directions by in and out motion of said plunger, spring means for re-

turning said plunger on release of fluid pressure thereon, and means effective to apply and release fluid pressure on said plunger.

4. A grinding machine having a work holder, a grinding wheel carriage, means for relatively moving said holder and carriage in a direction to feed a grinding wheel on said carriage relative to work on said holder, said moving means comprising a one direction driving clutch, an oscillatory shaft for driving said clutch, a fluid pressure actuated plunger connected to said shaft to rock said shaft in opposite directions by in and out motion of said plunger, spring means for returning said plunger on release of fluid pressure thereon, a latch engageable with said moving means and biased to hold said moving means stationary, fluid pressure means for first retracting said latch and then acting on said plunger, and means for controlling said fluid pressure means.

5. In combination with a movable carriage having a grinding wheel mounted thereon, a wheel truing device, means for moving said carriage to feed the grinding wheel relative to work and to said wheel truing device, said carriage moving means comprising a rotary shaft, connections from said shaft to said carriage causing rotation of said shaft to move said carriage, a gear fixed to said shaft, an externally threaded quill engaging the teeth of said gear, and mounted for axial and rotational motion, the threads of said quill acting as a rack with respect to the teeth of said gear on axial motion of said quill to effect normal feed of said wheel relative to the work and to said device, and acting as a worm on rotation of said quill to effect a further slight feed of said device relative to the wheel to compensate for wheel wear and truing, means for moving said quill axially, and means for rotating said quill.

6. A grinding machine having a work holder, a grinding wheel carriage, means for relatively moving said holder and carriage in a direction to feed and retract a wheel on said carriage relative to work on said holder, a pair of means selectively actuated by said feeding means for returning said feeding means to starting position after a predetermined extent of feed, one of said pair of means being set to permit a greater feed motion than the other pair of means, and means acting automatically on return of said feeding means to starting position by the action of the means of said pair set for the less feed for restoring said feeding means to feeding actuation.

7. A grinding machine having a work holder, a grinding wheel carriage, means for relatively moving said holder and carriage to effect traverse of said wheel along work carried by said holder, means for relatively moving said holder and wheel transverse to the line of traverse to produce relative feed between the work and wheel, a pair of movable stops one or the other of which may be made operative to limit the extent of feed, means for automatically moving said stops to position one of said stops into operative position to limit the feed and consequent depth of cut for a rough grinding operation and thereafter to position the other of said stops into operative position to limit the feed and consequent depth of cut during finish grinding, and means actuated by each stop when the feed is stopped thereby, to actuate said transverse moving means in reverse to separate the work and wheel to a predetermined feed starting position.

8. A grinding machine having a work carriage, a grinding wheel carriage, means for moving one of said carriages to produce a relative traverse

between said carriages, elements movable with said movable carriage defining traverse limits, a member with which said elements cooperate for effecting reversal of traverse directions, said member being movable to any of three positions to cooperate selectively with certain of said elements to thereby select the amplitude of traverse at one end to normal grinding, extended truing, or to and from a loading and unloading position, a truing device movable to and from operative position to true the wheel in said extended traverse, and means controlled by the position of said member to control the speed of traverse to a slow grinding speed while said member is in grinding position, to a slower speed when said member is in truing position and to operatively position said truing device so that the wheel is trued by said device during extended traverse, and to a fast speed when said member is in loading and unloading position.

9. A grinding machine having a work carriage, a grinding wheel carriage, means for moving one of said carriages to produce a relative traverse between said carriages, elements movable with said movable carriage defining traverse limits, a member with which said elements cooperate for effecting reversal of traverse directions, said member being movable to any of three positions to cooperate selectively with certain of said elements to thereby select the amplitude of traverse at one end to normal grinding, extended truing, or to and from a loading and unloading position, a truing device movable to and from operative position to true the wheel in said extended traverse, means controlled by the position of said member to control the speed of traverse to a slow grinding speed while said member is in grinding position, to a slower speed when said member is in truing position and to operatively position said truing device so that the wheel is trued by said device during extended traverse, and to a fast speed when said member is in loading and unloading position, and mechanism automatically moving said member in predetermined sequence from one to another of said positions to define a cycle of operations of the machine.

10. A grinding machine having a work carriage, a grinding wheel carriage, means for moving one of said carriages to produce a relative traverse between said carriages, elements movable with said movable carriage defining traverse limits, a member with which said elements cooperate for effecting reversal of traverse directions, said member being movable to any of three positions to cooperate selectively with certain of said elements to thereby select the amplitude of traverse at one end to normal grinding, extended truing, or to and from a loading and unloading position, a truing device movable to and from operative position to true the wheel in said extended traverse, means controlled by the position of said member to control the speed of traverse to a slow grinding speed while said member is in grinding position, to a slower speed when said member is in truing position and to operatively position said truing device so that the wheel is trued by said device during extended traverse, and to a fast speed when said member is in loading and unloading position, means for effecting relative feed and retraction between said carriages, and mechanism partly responsive to the relative feeding relation between said carriages for moving said member in predetermined sequence from one to another of said positions to define a cycle of operations of the machine.

11. A grinding machine having a work carriage, a grinding wheel carriage, means for moving one of said carriages to produce a relative traverse between said carriages, elements movable with said movable carriage defining traverse limits, a member with which said elements cooperate for effecting reversal of traverse directions, said member being movable to any of three positions to cooperate selectively with certain of said elements to thereby select the amplitude of traverse at one end to normal grinding, extended truing, or to and from a loading and unloading position, a truing device movable to and from operative position to true the wheel in said extended traverse, means controlled by the position of said member to control the speed of traverse to a slow grinding speed while said member is in grinding position, to a slower speed when said member is in truing position and to operatively position said truing device so that the wheel is trued by said device during extended traverse, and to a fast speed when said member is in loading and unloading position, means for effecting relative feed and retraction between said carriages, and mechanism partly responsive to the relative feeding relation between said carriages and partly responsive to the traverse relation between said carriages for moving said member in predetermined sequence from one to another of said positions to define a cycle of operations of the machine.

12. A grinding machine having a work carriage, a grinding wheel carriage, means for moving one of said carriages to produce a relative traverse between said carriages, elements movable with said movable carriage defining traverse limits, a member with which said elements cooperate for effecting reversal of traverse directions, said member being movable to any of three positions to cooperate selectively with certain of said elements to thereby select the amplitude of traverse at one end to normal grinding, extended truing, or to and from a loading and unloading position, a truing device movable to and from operative position to true the wheel in said extended traverse, means controlled by the position of said member to control the speed of traverse to a slow grinding speed while said member is in grinding position, to a slower speed when said member is in truing position and to operatively position said truing device so that the wheel is trued by said device during extended traverse, and to a fast speed when said member is in loading and unloading position, means for effecting relative feed and retraction between said carriages, means controlled by said feeding means when said carriages reach a predetermined relative feed position to condition said feeding and retracting means to retract said carriages relatively from said position, and mechanism actuated in part by the motion of said one carriage at a predetermined point in its traverse path and in part by said controlling means when so actuated, for moving said member in predetermined sequence from one to another of said positions to define an automatic cycle of operations of the machine.

13. A machine of the class described, comprising a tool carriage, a work holding carriage, means for moving one of said carriages to produce a relative traverse motion between said carriages, stops carried by said one carriage and projecting by different amounts therefrom, a member rockably mounted to be turned by impingement thereon of said stops adjacent to traverse limits of said one carriage, said member being mounted for ad-

justment toward and from said stops, a non-rockable axially movable member secured to said rockable member for simultaneous axial motion therewith, said non-rockable member having a plunger portion, connections from said rockable member to said carriage moving means causing the rocking of said rockable member by impingement of said stops thereon to reverse the direction of traverse, a fluid pressure cylinder within which said plunger portion extends, and means for controlling a supply of fluid pressure to said cylinder to thereby determine the axial position of said rockable member and thus determine the limits of traverse motion.

14. A machine of the class described, comprising a tool carriage, a work holding carriage, means for moving one of said carriages to produce a relative traverse motion between said carriages, stops carried by said one carriage and projecting by different amounts therefrom, a member rockably mounted to be turned by impingement thereon of said stops adjacent to traverse limits of said movable carriage, said member being mounted for adjustment toward and from said stops, a non-rockable axially movable member secured to said rockable member for simultaneous axial motion therewith, said non-rockable member having a plunger portion and a control portion, connections from said rockable member to said carriage moving means causing the rocking of said rockable member by impingement of said stops thereon to reverse the direction of traverse, a fluid pressure cylinder within which said plunger portion extends, means for controlling a supply of fluid pressure to said cylinder to thereby determine the axial position of said rockable member and thus determine the limits of traverse motion, and means controlled by the position of said control portion for determining the rate of motion of said one carriage.

15. A machine of the class described, comprising a tool carriage, a work holding carriage, means for moving one of said carriages to produce a relative traverse motion between said carriages, a tool carried by said tool carriage, means for moving one of said carriages transverse to the direction of traverse to feed said tool and work holding carriage relatively, stops carried by said traversing carriage and projecting different amounts therefrom, a member rockably mounted to be turned by impingement thereon of said stops adjacent to traverse limits of said traversing carriage, said member being mounted for adjustment toward and from said stops, a non-rockable axially movable member secured to said rockable member for simultaneous axial motion therewith, said non-rockable member having a plunger portion and a control portion, connections from said rockable member to said carriage moving means causing the rocking of said rockable member by impingement of said stops thereon to reverse the direction of traverse, a fluid pressure cylinder within which said plunger portion extends, means for controlling a supply of fluid pressure to said cylinder to thereby determine the axial position of said rockable member and thereby determining the limits of traverse motion, and means controlled by the position of said control portion to determine the limit of said feed motion.

16. A machine of the class described, comprising a tool carriage, a work holding carriage, means for moving one of said carriages to produce a relative traverse motion between said carriages, stops carried by one carriage and project-

ing by different amounts therefrom, a member rockably mounted to be turned by impingement thereon of said stops adjacent to traverse limits of said movable carriage, said member being mounted for adjustment toward and from said stops, a non-rockable axially movable member secured to said rockable member for simultaneous axial motion therewith, said non-rockable member having a plunger portion and a valve portion, connections from said rockable member to said carriage moving means causing the rocking of said rockable member by impingement of said stops thereon to reverse the direction of traverse, a fluid pressure cylinder within which said plunger portion extends, fluid pressure means for controlling a supply of fluid pressure to said cylinder to thereby determine the axial position of said rockable member and thus determine the limits of traverse motion, and fluid pressure means controlled by the position of said valve portion for determining the rate of motion of said one carriage.

17. A machine of the class described, comprising a tool carriage, a work holding carriage, means for moving one of said carriages to produce a relative traverse motion between said carriages, a tool carried by said tool carriage, work carried by said work carriage, means for moving one of said carriages transverse to the direction of traverse to feed said tool and work relatively, stops carried by said traversing carriage and projecting different amounts therefrom, a member rockably mounted to be turned by impingement thereon of said stops adjacent to traverse limits of said traversing carriage, said member being mounted for adjustment toward and from said stops, a non-rockable axially movable member secured to said rockable member for simultaneous axial motion therewith, said non-rockable member having a plunger portion and a valve portion, connections from said rockable member to said carriage moving means causing the rocking of said rockable member by impingement of said stops thereon to reverse the direction of traverse, a fluid pressure cylinder within which said plunger portion extends, means for controlling a supply of fluid pressure to said cylinder to thereby determine the axial position of said rockable member and thereby determining the limits of traverse motion, and fluid pressure means controlled by the position of said valve portion to determine the limit of said feed motion.

18. A machine of the class described, comprising a tool carriage, a work carriage, means for effecting relative traverse between said carriages, means producing relative feed between said carriages transverse to the direction of traverse, said traversing means including elements stopping the traverse at points defining the traverse limits, a movable member selectively cooperating with certain of said elements to determine by the position of said member which of said certain elements shall be effective, means actuated by said feed producing means at the feed limit for moving said movable member to a different position, and means controlled by said member in accordance with its position determining the speed of traverse.

19. A machine of the class described, comprising a grinding wheel carriage, a work carriage, means for traversing one of said carriages with respect to the other carriage, spaced stop elements carried by said traversing carriage and extending to different distances therefrom, the longest of said stops defining one limit of traverse

motion, a shorter stop defining the other limit of an extended traverse, and a stop of intermediate length defining the other limit of a working traverse, a rockable and axially movable member extending toward the path of motion of said stops and having three definite axial positions in all of which it is in the path of motion of said longest stop to be rocked in one direction by impingement of said longest stop thereon, in the inner of which axial positions said member is in position to be impinged upon by said shortest stop to be rocked thereby into another angular position, and in the intermediate of which positions it is not contacted by said shortest stop but is contacted and rocked to said other angular position by the stop of intermediate length, and in the outermost position said member is contacted by neither said shortest stop nor said stop of intermediate length, a wheel truing device positioned to act on a wheel carried by said wheel carriage during said extended traverse, operative connections between said member and traversing means causing rocking of said member by said stops to reverse the direction of traverse, and mechanism effective to position said member in each of said axial positions in a predetermined cycle.

20. A machine of the class described, comprising a tool carriage, a work carriage, means producing a relative feed between said carriages from a retracted position when a tool on said tool carriage is out of contact with work on said work carriage, means normally limiting the rate of such feed, a normally open switch, a rotary cam engaging said switch and having a surface portion positioned to close said switch, a latch normally holding said cam stationary in angular position permitting said switch to be open, a motor for turning said cam, an electrically operated device acting when energized to momentarily trip said latch allowing said cam to be turned and to close a circuit to said motor, said cam having a surface portion engaging and holding open said latch during a predetermined extent of rotation of said cam during which said switch is closed and then allowed to open, means for energizing said device at the start of such feed from the retracted position, and means responsive to the closing of said normally open switch and operative only so long as said switch remains closed for rendering inoperative said rate limiting means to increase the rate of feed to bring the work and tool close together after which said rate limiting means is effective to slow the rate of feed.

21. A machine of the class described, comprising a grinding wheel carriage, a wheel truing mechanism, means for presenting said mechanism in wheel truing position and then retracting said mechanism, a normally open switch, a rotary cam engaging said switch and having a surface portion positioned to close said switch, a latch normally holding said cam stationary in angular position permitting said switch to be open, a motor for turning said cam, an electrically operated device acting when energized to momentarily trip said latch allowing said cam to be turned and to close a circuit to said motor, said cam having a surface portion engaging and holding open said latch during a predetermined extent of rotation of said cam during which said switch is closed and then allowed to open, means energizing said device when said mechanism presenting means is conditioned to present such mechanism in wheel truing position, and means actuated by the closing of said switch to feed said mecha-

nism and carriage relatively to compensate for wheel wear and truing.

22. A grinding machine having a work holder, a grinding wheel carriage, hydraulically actuated means for relatively moving said holder and carriage in a direction to feed a wheel on said carriage relative to work on said holder, means actuated by said feeding means after a predetermined amount of feed for returning said feed means to starting position, means acting automatically thereafter to restore said feeding means to feeding actuation, and means actuated by said feeding means automatically after a predetermined amount of feed larger than the amount for said first feeding motion to return said feeding means to starting position.

23. A grinding machine having a work holder, a grinding wheel carriage, means for relatively moving said holder and carriage to effect traverse of said wheel along work carried by said holder, means for relatively moving said holder and wheel transverse to the line of traverse and during such traverse to produce relative feed between the work and wheel, a pair of stops one or the other of which may be made operative to limit the extent of feed, and means for automatically moving both stops to position one of said stops into operative position and the other out of operative position to limit the feed and consequent depth of cut for a rough grinding operation and thereafter to position the other of said stops into operative position and said one stop out of operative position to limit the feed and consequent depth of cut during finish grinding.

24. A machine of the class described, comprising a tool carriage, a work carriage, means for moving one of said carriages relative to the other carriage to effect relative traverse between said carriages, means for moving one of said carriages relative to the other carriage transverse to the direction of traverse to effect a relative feed and retraction between said carriages, said traverse moving means including a reversing member movable to control the direction of traverse, elements carried by the movable carriage for actuating said reversing member to reverse the traverse direction, said member being movable into and out of cooperative relation to certain of said traverse reversing actuating elements to selectively limit the length of traverse in accordance with the position of said member relative to said elements, feed limiting elements selectively positioned to control said feed moving means to limit the feed between said carriages to different amounts, and means actuated by the feed moving means through the limiting element selected at any one time to determine the position of said member and thus the limit of traverse of the next succeeding traverse motion.

25. A machine of the class described, comprising a tool carriage, a work carriage, means for moving one of said carriages relative to the other carriage to effect relative traverse between said carriages, means for moving one of said carriages relative to the other carriage transverse to the direction of traverse to effect a relative feed and retraction between said carriages, said traverse moving means including a reversing member movable to control the direction of traverse, elements carried by the movable carriage for actuating said reversing member to reverse the traverse direction, said member being movable into and out of cooperative relation to certain of said traverse reversing actuating elements to selectively limit the length

of traverse in accordance with the position of said member relative to said elements, feed limiting elements movable to position one or another in cooperative relation to said feed moving means to control said feed moving means to limit the feed between said carriages to different amounts depending upon which element is in cooperating position, means actuated by the feed moving means through the limiting element in cooperative relation to said feed moving means at any one time to determine the position of said member and thus the limit of traverse of the next succeeding traverse motion, and means controlled by said member in accordance with its position for determining the speed of traverse.

26. A machine of the class described having a tool carriage, a work carriage, means for moving one of said carriages relative to the other carriage to effect relative traverse between said carriages, said means including a member operable to reverse the direction of traverse and movable from one to another of a plurality of operative positions, traverse stops carried by that carriage which is movable for traverse each stop cooperating with said member in certain of the operative positions of said member to selectively determine the length of traverse, means for moving one of said carriages to effect relative feed and retraction between said carriages transverse to the line of traverse, a feed stop carrier, a plurality of feed stops set for different feed limits carried by said carrier, means for moving said carrier to present any of said feed stops selectively into operative position, means for moving said member from one to another of its operative positions, and mechanism controlled partly by said carrier and partly by said carriages in accordance with their relative positions actuating said member moving means, said carrier moving means, and both of said carriage moving means in a predetermined cycle.

27. A machine of the class described having a tool carriage, a work carriage, means for moving one of said carriages relative to the other carriage to effect relative traverse between said carriages, said means including a member operable to reverse the direction of traverse and movable from one to another of a plurality of operative positions, traverse stops carried by that carriage which is movable for traverse each stop cooperating with said member in certain of the operative positions of said member to selectively determine the length of traverse, means for moving one of said carriages to effect relative feed and retraction between said carriages transverse to the line of traverse, a feed stop carrier, a plurality of feed stops set for different feed limits carried by said carrier, fluid pressure means for moving said carrier to present any of said feed stops selectively into operative position, means for moving said member from one to another of its operative positions, and electrical mechanism controlled partly by said carrier and partly by said carriages in accordance with their relative positions actuating said member moving means, said carrier moving means, and both of said carriage moving means in a predetermined cycle.

28. A grinding machine having a work holder, a grinding wheel carriage, means for relatively moving said holder and carriage to effect traverse of said wheel along work carried by said holder, means for relatively moving said holder and wheel transverse to the line of traverse and during such traverse to produce relative feed be-

tween the work and wheel, a movable member, a pair of stops carried by said member one or the other of which may be made operative by movement of said member to limit the extent of feed and to return said holder and wheel to starting feed relation, and means for automatically moving said movable member to position one of said stops into operative position to limit the feed and consequent depth of cut for a rough grinding operation and the other stop out of operative position and thereafter moving said movable member to position said one stop out of operative position and the other of said stops into operative position to limit the feed and consequent depth of cut during finish grinding.

29. A grinding machine having a work holder, a grinding wheel carriage, means for relatively moving said holder and carriage to effect traverse of said wheel along work carried by said holder, means for relatively moving said holder and wheel transverse to the line of traverse to produce relative feed between the work and wheel, a pair of movable stops one or the other of which may be made operative to limit the extent of feed, and means for automatically moving said stops simultaneously to position one of said stops into operative position to limit the feed and consequent depth of cut for a rough grinding operation and while the other stop is moved out of operative position and thereafter to position the other of said stops into operative position to limit the feed and consequent depth of cut during finish grinding and while said one stop is moved out of operative position.

30. A grinding machine having a work holder, a grinding wheel carriage, means for relatively moving said holder and carriage to effect traverse of said wheel along work carried by said holder, means for relatively moving said holder and wheel transverse to the line of traverse and during such traverse to produce relative feed between the work and wheel, a pair of stops both movable together to present one or the other operative to limit the extent of feed while the other is out of operative position, means for automatically moving said stops to position one of said stops into operative position and the other out of operative position to limit the feed and consequent depth of cut for a rough grinding operation and thereafter to move said stops to position the other of said stops into operative position and said one stop out of operative position to limit the feed and consequent depth of cut during finish grinding, means for automatically truing the wheel between the rough and finish grindings, and supplemental means for automatically actuating said feed means an additional amount independent of said stops, to compensate for wheel wear and truing preparatory to truing the wheel.

31. A machine of the class described comprising a tool carriage, a work supporting carriage, means for effecting relative traverse between said carriages, means for producing a relative feed between said carriages transverse to the direction of traverse, said traversing means including elements defining different traverse limits, a movable member selectively cooperating with certain of said traverse elements to determine by the position of said member which of said certain elements shall be effective, said feed means including elements defining different feed limits, means actuated by said feed producing means at any of said feed limits for moving said movable member to a different position to

thereby change from one to a different feed limit defining element effective and to thereby change a traverse limit, and means actuated by said traversing means at a predetermined traverse position and in a predetermined direction to 5 change the position of said movable member.
